UNITED STATES PATENT OFFICE.

GEORGE H. THACHER, JR., OF MELROSE, MASSACHUSETTS.

STOKER BAR.

Application filed October 9, 1923. Serial No. 667,514.

To all whom it may concern:

Be it known that GEORGE H. THACHER, Jr., a citizen of the United States, and a resident of Melrose, in the county of Middlesex and State of Massachusetts, has invented an Improvement in Stoker Bars, of which the following description, in connection with the accompanying drawings, is a specification, like characters on the drawings representing like parts.

The present invention relates to furnaces and great surfaces therefore and particularly to the type known as hand-stokers wherein combustion takes place upon an inclined fuel surface composed of a plurality of transverse great or stoker bars. The invention aims to provide a novel and improved stoker bar and grate surface therefor, and will best be understood from a description of one selected embodiment thereof, reference being had to the accompanying drawings illustrating the same, and wherein,—

Figure 1 is a top plan view of the stoker bar, being one of a series of like bars;

Fig. 2, a detail perspective side view of the same, all but one of the grate sections having been removed;

Figs. 3 and 4 transverse vertical sections of the stoker bar frame from which the grate sections have been removed, on the lines 3—3 and 4—4 of Fig. 1, showing the inner faces of the end plates, respectively;

Fig. 5, a rear face view of the removable cross bar between the end plates for supporting the grate sections;

Figs. 6, 7 and 8, vertical sectional views of the removable cross-bar on the lines 6—6, 7—7, and 8—8 respectively of Fig. 5;

Figs. 9 and 10, detail longitudinal sections of portions of the stoker bar showing the extremities of the removable cross-bar;

Figs. 11, 12 and 13 top, rear end, and side views respectively of a grate section on an enlarged scale.

Referring to the drawings, the stoker bar herein shown and illustrating one selected embodiment of my invention, is designed to be used in a furnace of the hand-stoking type and of the general character shown in my United States Patents Nos. 1,302,453 and 1,453,482, wherein a plurality of stoker bars are mounted to rock on inclined bearing-bars extending from the front to the rear of the furnace and wherein the stoker bars are connected together usually in two series, to rock independently, thereby to advance

the fuel toward the lower end or rear of the furnace and to clean the stoker bars.

In the embodiment of the invention herein illustrated the improved stoker bar comprises a frame and a separate movable grate surface free to be moved into and out of operative position on the frame. This frame is an open structure preferably quadrilateral in form when viewed from the top and comprises vertically arranged end plates 15, 16 positioned at opposite ends of the bar and connected on the rear side, which is toward the lower end of the furnace, by a cross-bar 17 and on the front side by a curved shield 18. The outer face of each end plate has a trunnion 19 adapted to seat in a recess in the bearing-bar on the corresponding side of the stoker for supporting the stoker-bar, these trunnions being so positioned that when the stoker bar is rocked its front side, including the shield 18, swings above the top surface of the stoker.

The shield 18 is provided with a number of transverse apertures 20, 20 etc. distributed preferably at regular intervals over its surface to permit the passage of air therethrough and also into the fuel bed when the stoker bar is rocked. One or more of these apertures may receive bolts 21 for connecting a lug 22 to one end of the shield, by means of which the bar is operatively connected to actuating mechanism. This lug is provided with an upper portion 23 having the same curvature as the inner face of the shield and is provided with holes arranged to register with holes in the shield at the point of attachment. Those openings in the shield which are utilized for this purpose are preferably countersunk to receive the bolt heads which lie flush with the outer face of the shield to avoid projections interfering with the operation of the stoker bar.

The upper edge of the shield 18 has a flat surface which forms a straight supporting ledge or seat 24 on which the front ends of the grate sections 25, 25, etc. are arranged to lap in movable relation, this ledge or seat being disposed well below the upper surface of the stoker and at a depth commensurate with the overlying portions of the grate sections which lie flush with all the remaining grate sections constituting the upper face of the stoker. This ledge or seat 24 is provided with semi-circular recesses 26, forming air-cooling passages, distributed at regular intervals throughout its length.

The cross-bar 17, which supports the rear ends of the grate sections, is a separate removable element supported in and connecting the end plates 15, 16, but without any positive locking connection and free to be lifted out of and restored to its normal position within the frame. This element is designed to provide a firm support for the grate sections, being free to expand or contract under changing thermal conditions without warping or cracking but movable in respect to one end plate only during such expansion and contraction.

The top of the bar forms a flat supporting surface 27 substantially parallel with the top surface of the grate sections, while the sides are arranged at an inclination to each other due to the gradual thickening of the bar in cross-section, proceeding from top to bottom, at which point there is provided on the rear side a slight reinforcing lip or web 28 extending approximately the entire distance between the end plates and designed to prevent warping of the bar lengthwise. The extremities of the bar extend freely into recesses provided on the inner faces of the end plates, one of these recesses forming an enclosed socket 29 conforming generally in outline to the corresponding end of the cross-bar which is introduced therein as the first operation in placing the bar in position on the frame. The bottom wall of this socket forms a ledge on which the cross-bar rests and is preferably extended outward by the provision of a shoulder 30 at the same elevation on the inner face of the end-plate. This extension or shoulder is adapted to serve initially as a guide to insertion of the bar into the socket and also to insure prevention of downward displacement of the bar during rapid or excessive contraction of the bar from any cause.

The opposite end of the supporting bar carries a head 31 conforming generally in outline to an obliquely arranged slot or recess 32 in the corresponding end plate 16, said slot communicating at its upper end with the top edge of the bar and at its lower end with a well or recess 33 into which a reduced portion 34 on the bottom of the head 31 freely extends, said reduced portion being adapted to operate as a stop for preventing lengthwise movement of the bar at this end during expansion and contraction. This construction tends to prevent ash from lodging in the recess 32 and, by inducing greater relative movement in the bar, also serves to prevent adherence or pinning of the grate sections to the bar due to fusion or clinkers and consequent warping effects.

The diagonal position of the head 31 cooperates with the grate sections 25 as herein-after more fully explained, to prevent upward or outward displacement of the bar 17 when the stoker bar is rocked. This end of

the bar 17 bears movably upon a horizontal support formed by the upper edge of an integral lateral extension portion 35 of the end plate 16 and extending across the lower end of the slot 32 and enclosing the well 33 (see Fig. 10). A sufficient clearance is provided on all sides of the head 31 to allow for necessary expansion.

Each of the grate sections 25 has a grated upper surface for fuel support formed of a number of spaced longitudinal members 40 connected together at one end by an integral transverse member 41 and at the opposite end by an integral transverse member 42. Each of these transverse members projects at both ends beyond the sides of the grate section a distance preferably somewhat less than half of the space between adjacent longitudinal members so that when the several grate sections are all arranged in normal operative position a slight space will intervene between corresponding ends of adjacent sections while the spaces between the outer longitudinal elements 40 of one grate section and the corresponding elements of another section will be substantially of the same width as the enclosed openings of each grate section.

The grate sections 25 are all slidably mounted in the frame on the bar 17, the front ends of the sections being extended forward to lap onto the upper edge 24 of the shield 18, which is thus provided with an upward extension and a protective covering from the fuel bed. The upper surface of the grate sections is designed to lie flush with the tops of the end-plates 15, 16 while the front face conforms to the arc of the outer face of the shield. The two outer longitudinal members 40 are each provided at the rear end, which is toward the lower end of the furnace, with a downward extension 44 (see Figs. 2 and 13) having a transverse tapering cleft 43 extending well upward into the body portion of said members and nearly commensurate with the height of the bar 17, which extends into it. These clefts or slots form a channel of sufficiently ample proportions to allow a clearance of adjacent parts at all times, to the end that the grate sections separately or collectively may be free to be removed from and restored to their setting in any state of temperature, and, also, that their resulting free play may tend to discharge ash sifting down from the fuel bed.

The jaws formed by the lower extremities of the extensions 44 are directed against and impinge upon bar 17 during the stoking process and serve to prevent the grate sections from working off the bar when the stoker bar is rocked, and particularly when excessive upward pressure is exerted upon the forward end of any of the grate sections by fuel or clinkers penetrating between the

grate sections and the shield during the stoking process. Occasionally at such times one or more of the grate sections may be slightly lifted from its setting, but complete displacement is prevented by the effective resistance offered by the impingement of the jaws of the lower portion 44 upon the bar 17 as before stated. Hence, while the grate sections are at all times movable with respect to each other and free to be removed from normal position by a direct upward pull, their displacement by force exerted in other or indirect lines oblique to the supporting surfaces 24, 27, is prevented in the manner described.

The outer face of the rear transverse member 42, which is in alignment with the trunnions 19, is rounded in outline to avoid contact with the adjacent stoker bar when rocked and is also preferably fluted or otherwise suitably roughened to provide teeth 45 for breaking up any clinkers or lump fuel which may tend to become imbedded in the stoker surface, the channels 25 or interstices between said teeth being adapted to admit air to the fuel bed.

In assembling the parts of the stoker bar, the supporting bar 17 is first mounted in position on the end plates. In so doing one end of the bar is first inserted in the recess 29 and then the opposite end bearing the head 31 is dropped into place. The grate sections are now placed separately in position until the entire space between the end 35 plates is filled. These sections may be removed in like manner when necessary, being carried on the bar 17 without any locking connection whatever and free to expand or contract in any direction.

40 The weight of the fuel tends normally to maintain the grate sections in position while any force applied by the fuel upon the front end of the grate sections during the upward or downward swing of the bar, 45 tending to dislodge the grate sections or lift the supporting bar out of place, is successfully opposed with respect to the former elements in the manner hereinbefore related, and also with respect to the latter 50 element by reason of the angular position of the head 31, to remove which force must be applied in the line of the head and the recess in which it rests, this being in a direction opposite to that of the force exerted by the dislodging fuel.

It is quite usual for grate bars to wear, burn out or crack at some specific point or points in their fuel area and not uniformly at all points. This is attributed to excess 60 of heat at localized spots or, what is more generally the case, to improper or unequal distribution of the metal, so that expansion or contraction takes place more rapidly at one point than another, thus resulting in 65 undue internal strains which cause warping

and rupture. With the present device these objections are largely overcome. The provision and arrangement of air cooling passages is so co-ordinated with the weight and thickness of the surrounding metal that expansion and contraction of each of the grate sections at all points may be accomplished without injury, while the overlay of metal directly above the shield 18 and the supporting bar 17 is adequate to prevent overheating and warping of these parts.

It should be understood that the present invention is not restricted to the particular embodiment herein shown, and that obvious modifications may be made therein without departing from the scope of the invention.

I claim as my invention:

1. In a rocking stoker bar, in combination, a frame having end plates, a member connecting the end plates and forming a shield adapted to swing above the upper face of the stoker when the stoker bar is rocked, a series of free grate sections mounted in the frame and normally movable in their operative position, a carrier bar carried on said end plates and furnishing support for the grate sections, said grate sections being independently removable and said carrier bar and grate sections being free to be removed together and restored to operative position in the frame, and non-locking retaining means for securing the carrier bar in operative position when the stoker bar is rocked.

2. In a stoker bar, in combination, a frame having end members, and a member connecting the end members and forming a shield on the front side of the frame, a series of grate sections movably mounted in the frame, a freely removable carrier bar carried on said end members and furnishing support for the grate sections, each of said grate sections being free to be lifted out of and restored to operative position without disturbing the position of the frame or carrier bar, and non-locking retaining means normally securing the carrier bar in operative position.

3. In a rocking stoker bar, in combination, a frame with end members each having a recess on its inner face, one of such recesses forming a socket and the remaining recess forming a channel communicating with the top edge of the respective end member, a carrier bar carried on said end members and extending at opposite ends into said recesses, a member connecting the end members on the front side of the frame and forming a shield, and a freely removable grate portion mounted in the frame and receiving support from the carrier bar, the front end of said grate portion being arranged to lap onto and cover said shield.

4. In a rocking stoker bar, in combination, a frame having end plates, a member

- connecting the end plates and forming a shield on the front side of the frame adapted to swing above the upper face of the stoker when the stoker bar is rocked, a series 5 of grate sections mounted in the frame and normally movable in the operative position, each grate section having a transverse cleft at its rear end, a carrier bar carried on the end portions of the frame and extending 10 into said clefts in the grate sections and furnishing support therefor, each of said grate sections being free to be removed from and restored to operative position without disturbing the position of the carrier bar, and 15 non-locking retaining means normally securing the carrier bar in operative position.
5. In a stoker bar, in combination, a grate portion, and a frame comprising end members each having a recess on its inner face 20 and a lateral extension member forming a horizontal support arranged adjacent the bottom of the corresponding recess and projecting beyond the plane of said inner face of the end member, means for rigidly securing 25 the end members together, and a bar extending at opposite ends into said recesses in the end members and movably bearing upon said horizontal supports for furnishing support for the grate portion, said bar being 30 free to be lifted from and restored to operative position on the end members.
6. In a stoker-bar, a frame having end members each provided on its inner face 35 with a recess and presenting a bar support adjacent the lower extremity of such recess; a free grate-supporting bar carried on the end members and arranged to extend at its opposite extremities into said recesses for engagement with said supports; and means 40 for preventing lengthwise displacement of the grate supporting bar at one of its ends, including stop means on the bar for engaging one of said bar supports, said bar being supported at its other end for free end- 45 wise movement relatively to the corresponding bar support and to the grate.
7. A stoker bar comprising, in combination 50 a grate portion and a grate supporting frame comprising end members each having a recess on its inner face, one of such recesses forming a slot communicating with the upper edge of the corresponding end member and inclined toward the front side of the bar, a fixed member connecting the end 55 members on one side of the frame and forming a curved shield adapted to swing above the upper face of the stoker when the stoker bar is rocked, a normally movable free bar

supported on the end members and extending at opposite ends into said recesses, said bar having an angularly disposed fixed head at one end free to be inserted into and withdrawn from said slot in one of the end members and providing non-locking retaining means for preventing outward displacement 60 of the bar and grate portion when the stoker bar is rocked.

8. In a rocking stoker bar, in combination, a frame having end plates, each provided with a recess on its inner face, one of said recesses being inclined toward the rear side of the frame and communicating with the top edge thereof, and a freely removable bar carried on the end plates and extending at 70 opposite ends into said recesses, and a free grate portion mounted in said frame and receiving support from said bar, said bar and end members being cooperatively adapted to provide non-locking retaining means for preventing outward displacement of the 75 bar and the grate portion when the stoker bar is rocked.

9. In a device of the class described, in combination, a frame having end members and a side member connecting the end members, a grate portion mounted in the frame and comprising a plurality of removable free sections, a free bar carried on the end members of the frame and furnishing support for said grate sections, and means carried on the bar and co-operating with means on the end members of the frame for limiting lengthwise movement of said bar in one direction to prevent adherence of the grate sections to the bar.

10. In a rocking stoker bar, in combination, a frame having end members and a member connecting the end members on the front side of the frame and forming a shield, a free carrier bar supported on said end members, a grate portion mounted on said carrier bar and lapping at its front side onto said shield, said grate portion being free to be removed from and restored to operative position in the frame without disturbing said carrier bar, the mounting for said grate portion on the carrier bar, including a member extending below the body of the grate portion and having a deep transverse cleft formed therein for freely receiving said carrier bar thereby forming non-locking retaining means for said grate portion.

In testimony whereof I have signed my name to this specification.

GEORGE H. THACHER, Jr.
